UNITED STATES PATENT OFFICE

HARRY W. KRAG, OF ST. LOUIS, MISSOURI, ASSIGNOR TO AMERICAN SHOE MACHINERY AND TOOL COMPANY, OF ST. LOUIS, MISSOURI, A CORPORATION OF MISSOURI

SEWING MACHINE

Application filed September 8, 1931. Serial No. 561,556.

The invention relates to sewing machines, particularly to shoe sole sewing machines of the kind wherein the stitches are located the desired distance from the edge of the shoe sole by means of an adjustable edge gage which is so positioned with reference to the awl securing means as to necessitate the removal of the edge gage from the machine in order to remove and replace the awl. The principal object of the present invention is to provide a machine of the above type with an adjustable edge gage which will permit removal and replacement of the awl without removing the edge gage from the machine. Another object is to provide means for defining the operative range of the edge gage, which means may be operated to permit the edge gage to swing beyond such operative range to an inoperative position that is clear of the awl securing means. Other objects are simplicity and cheapness of construction, ease of operation and compactness of design. The invention consists in the edge gage and in the construction, combinations and arrangements of parts hereinafter described and claimed.

In the accompanying drawings, which form part of this specification and wherein like symbols refer to like parts wherever they occur,

Fig. 1 is a side view of a portion of a shoe sole sewing machine provided with an edge gage embodying my invention, the edge gage being shown in its normal operative position;

Fig. 2 is a front elevation of the parts shown in Fig. 1;

Fig. 3 is a bottom plan view thereof;

Fig. 4 is a view similar to Fig. 1 showing the edge gage swung outwardly beyond its normal operative range so that access may be had to the awl securing device;

Fig. 5 is a vertical section on the line 5—5 in Fig. 2;

Fig. 6 is a horizontal section on the line 6—6 in Fig. 2; and

Fig. 7 is a horizontal section on the line 7—7 in Fig. 2.

Referring to the accompanying drawings,

my invention is shown in connection with a shoe sole sewing machine of the curved needle and awl type comprising a stitcher head 1, a feed slide 2 slidably supported in said stitcher head and a curved awl 3, which is removably secured by means of a clamping bolt 4 and nut 5 to an oscillatory awl holder in the form of a segment gear 6 that is mounted on a longitudinal shaft 7 in the upper end of said feed slide. The machine is also provided with an edge gage 8, which is located between the awl 3 and the stitcher head 1, for guiding the shoe sole by contact with an edge thereof; and the machine is also provided with a suitable shoe guard 9, which is located in front of said awl and is adapted for movement with said edge gage. The construction of the shoe sole sewing machine thus far described is well known and it is considered unnecessary to illustrate it in detail.

As shown in the drawings, the edge gage 8 and shoe guard 9 forms part of an attachment or fixture comprising a horizontally disposed bracket member 10 of substantially angle shaped cross-section which is fitted on the front upper corner of the stitcher head with its top flange overlapping the adjacent base portion of the feed slide 2 for retaining said portion in the slideway provided therefor in said stitcher head. The top flange of the angle-shaped bracket 10 is removably secured to the stitcher head 1 preferably by means of screws 11; and said flange is also preferably provided with oil cups 12 for supplying oil to the cooperating surfaces of said flange and the base portion of said feed slide 2. The edge gage 8 and shoe-guard 9 are mounted on the upper arm of a rock lever 13 that is fixed, preferably by means of a set screw 14, to a horizontally disposed rock shaft 15, whose ends are journaled in suitable bearings 16 provided therefor on the top flange of the angle-bracket 10. The edge gage 8 is secured to the upper arm of the rock lever 13 by means of screws 17 that extend through vertically elongated slots in said gage, thereby permitting vertical adjustment of said edge gage. The shoe guard 9 is secured to the upper arm of the rock lever 13 by means of

screws 18, the lower one of which extends through an arcuate slot 19 in said guard having a curvature which permits limited adjustment of the shoe guard about the axis of the 5 uppermost screw.

The rock lever 13 is actuated by means of a horizontally disposed crank shaft 20 which is journaled in split bearings 21 provided therefor on the front face of the vertical 10 flange of the angle bracket 10. One end of the crank shaft 20 terminates adjacent to the lower arm of the rock lever and is provided with an integral head portion 20^a having a crank pin 22 projecting therefrom which engages 15 a block 23 that is mounted in a longitudinal slideway 24 provided therefor in the adjacent side face of said lower arm of said rock lever. The split bearings 21 are provided with clamp screws 25 and nuts 26 for obtaining 20 an amount of friction between said bearings and the crank shaft 20 journaled therein sufficient to prevent rotation of the crank shaft by the pressure of the shoe against the edge gage 9. The crank shaft 20 is provided 25 at its other end with a hand lever 27 having a split hub 28 which is rigidly clamped to said shaft by means of a clamp screw 29. By this arrangement, edge gage 8 may be adjusted to locate the stitches the 30 desired distance from the edge of the shoe sole by swinging the hand lever 27, thereby rocking the crank shaft 20 which, by reason of its crank pin connection 22 with the slide block 23 in the lower arm of the rock lever 13, causes said rock lever to pivot in its axis and swing the edge gage on its upper arm towards or away from the awl 3.

The normal operative range of the edge gage is defined by means of a horizontally 40 disposed stop pin 30 which is mounted in the depending flange of the bracket 10 for co-operation with two circumferentially spaced radially extending shoulder portions 31 and 32, respectively, formed on the hub 28 of the 45 hand lever 27. The shoulder 31 abuts against the stop pin 30 and limits the outward swinging movement of the hand lever 27; and the other shoulder 32 abuts against the said stop pin and limits the inward movement of the 50 hand lever, the shoulder 32 being formed by a portion of one wall of the split in the hub 28 of said hand lever the inner end portion of the other wall being cut away so as to clear 55 the adjacent end of said pin. The stop pin 30 is mounted for axial sliding movement in a horizontal bore provided therefor in the lower end of the vertical flange of the bracket 10 and is normally held in the path of the 60 shoulders 31 and 32 on the hub 28 of the hand lever 27 by means of a coil spring 33 mounted in said bore between the inner end thereof and the inner end of said pin. As shown in the drawings the stop pin 30 is provided with 65 a radially projecting manually operable pin

34 which projects through a notch 35 provided therefor in the bracket. One wall of said notch is provided with a cam surface 35^a adapted to force the stop pin 30 inwardly clear of the hand lever 27 when the radial pin 34 is swung downwardly along said cam surface.

As shown in the drawings, the edge gage 8 operates between the awl 3 and the feed slide 2; and, in order to prevent damage to the machinery, the normal operative range of said edge gage is limited so that the gage cannot be swung outwardly into the path of said awl or inwardly into the path of said feed slide. This adjustment of said gage is accomplished preferably by first swinging the hand lever 27 outwardly until the shoulder 31 abuts against the stop pin 30, then releasing said hand lever from the crank shaft 20 by loosening the clamping screw 29 and then inserting a pin wrench in a radial hole 36 provided therefor in the head 20^a of said crank shaft and rotating said shaft to bring the edge gage 8 the desired distance from the awl 3. The hand lever 27 is then locked to the crank shaft 20 by tightening the clamp screw 29. With the parts thus adjusted, the rear position of the edge gage 8 is reached when the hand lever 27 is swung rearwardly with the shoulder 32 on its hub 28 abutting against the stop pin 30. In this position of the hand lever, the edge gage clears the feed slide and the crank pin 22 is preferably at the limit of its inward movement, whereby said edge gage will always clear the feed slide regardless of the position of the hand lever relative to said crank pin. As stated above, the normal operative range of the edge gage is defined by the shoulders 31 and 32 on the hand lever 27. However, such normal operative range may be varied by releasing the hand lever 27 from the crank shaft and by rotating said crank shaft relative to said hand lever to change the position of the crank pin 22 relative to the shoulders 31 and 32. With this arrangement, the throw of the edge gage may be varied without changing the angular movement of the crank pin.

As stated above, the edge gage is, at all points of its normal operative range, located in front of the awl clamping nut 5 and thus prevents access to said nut when it is desired to remove and replace the awl 3. However, access may be readily had to the awl clamping nut 5 by releasing the stop pin 30, which defines the normal operative range of the edge gage, and then swinging the hand lever 27 outwardly until the crank pin 22 has reached the limit of its outward movement, in which position the upper arm of the rock lever will have swung outwardly far enough beyond its normal operative range to carry the edge gage clear of the awl clamping nut and thus permit access to be had to the awl. It is noted that it is necessary for the awl

to be in its retracted position before the edge gage can be swung clear of the awl clamping nut.

Obviously, the hereinbefore described construction admits of considerable modification without departing from the invention. Therefore, I do not wish to be limited to the precise details of construction shown and described.

10. What I claim is:

1. In a sewing machine, an awl, securing means therefor, an edge gage pivotally mounted on said machine for swinging movement across the securing means for said awl 15 to vary the distance between the latter and the edge of the work, means for swinging said edge gage, means for defining the normal operative range of swinging movement of said edge gage, and means for releasing said last 20 mentioned means to permit said edge gage to swing beyond its normal operative range to permit access to be had to said awl securing means.

2. In a sewing machine, an awl, an edge gage pivotally mounted on said machine adjacent to said awl for varying the distance between the latter and the work, means for varying the normal operative range of such pivotal movement of said edge gage, and 25 means for permitting said edge gage to swing beyond its normal operative range of pivotal movement to an inoperative position.

3. In a sewing machine, an awl, an edge gage mounted on said machine for swinging movement relative to said awl to determine the position of the edge of the work relative to said awl, a stop for defining the normal operative range of swinging movement of said edge gage, and means for releasing said 35 stop to permit said edge gage to swing beyond its normal operative range.

4. In a sewing machine, an awl, securing means therefor, an edge gage mounted on said machine for swinging movement across the securing means for said awl to position the edge of the work relative to said awl, a stop for defining the normal operative range of said edge gage, and means for releasing said stop to permit said edge gage to swing 45 beyond its normal operative range far enough to permit access to be had to the awl securing means.

5. In a sewing machine, an awl, securing means therefor, an edge gage mounted on said machine for swinging movement across the securing means for said awl to vary the distance between said awl and said edge gage, a stop for defining the normal operative range of such swinging movement of said 55 edge gage, means for varying the normal operative range of such swinging movement of said edge gage, and means for releasing said stop to permit said edge gage to swing beyond its normal operative range of swinging movement.

6. In a sewing machine, an awl, securing means therefor, an edge gage mounted on said machine for swinging movement across the securing means for said awl, to vary the distance between the awl and the edge of the work in engagement with said edge gage, a stop for defining the normal operative range of such swinging movement of said edge gage, means for varying the normal operating range of said edge gage, and means for releasing said stop to permit said edge gage to swing beyond its normal operative range without changing the setting of the means for varying the normal operative range of swinging movement of said edge gage. 65

7. In a sewing machine, a stitcher head, a feed slide, an awl support, an awl spaced from said stitcher head, means for securing said awl to said awl support, an edge gage mounted on said stitcher head for swinging movement towards and away from said stitcher head in the space between said awl and said stitcher head and across said awl securing means, means for limiting the normal operative range of such swinging movement of said edge gage to the space between said stitcher head and said awl, and means for releasing said last mentioned means to permit said edge gage to swing beyond its normal operative range of swinging movement far enough to permit access to be had to the awl securing means. 75

8. In a sewing machine, a stitcher head, a feed slide, an awl spaced from said stitcher head, an edge gage mounted on said stitcher head for swinging movement between and towards and away from said awl and said stitcher head, means for limiting the normal operative range of such swinging movement of said edge gage to the space between said stitcher head and said awl, and means for releasing said last mentioned means to permit said edge gage to swing beyond its normal operative range. 85

9. An edge gage for a sewing machine comprising a bracket adapted to be secured to said machine, a lever journaled in said bracket, an edge gage mounted on one arm of said lever, a block slidably mounted in the other arm of said lever, and a crank shaft journaled in said bracket and having a crank pin operatively engaging the block in said other arm of said lever. 95

10. An edge gage for a sewing machine comprising a bracket adapted to be secured to said machine, a lever journaled in said bracket, an edge gage mounted on one arm of said lever, a crank shaft journaled in said bracket and having a crank pin operatively engaging the other arm of said lever, a hand lever adjustably secured to said crank shaft, and a releasable stop pin cooperating with annularly spaced faces on said hand lever for limiting the swinging movement of said hand lever in both directions. 105

11. An edge gage for a sewing machine comprising a bracket adapted to be secured to said machine, a lever journaled in said bracket, an edge gage mounted on one arm 5 of said lever, a crank shaft journaled in said bracket and having a crank pin operatively engaging the other arm of said lever, a hand lever adjustably secured to said crank shaft, a stop pin for limiting the swinging movement of said hand lever, and means for rendering said stop pin inoperative.

12. An edge gage for a sewing machine comprising a bracket adapted to be secured to said machine, a lever journaled in said bracket, an edge gage mounted on one arm of said lever, a crank shaft journaled in said bracket and having a crank pin operatively engaging the other arm of said lever, a hand lever adjustably secured to said crank shaft, 20 a stop pin for limiting the swinging movement of said hand lever, means for rendering said stop pin inoperative, and means for preventing rotation of said crank shaft under the ordinary working pressure on the edge 25 gage.

13. An edge gage for a sewing machine comprising a bracket adapted to be secured to said machine, a lever journaled in said bracket, an edge gage mounted on one arm 30 of said lever, a crank shaft journaled in said bracket and having a crank pin operatively engaging the other arm of said lever, a hand lever adjustably secured to said crank shaft, a stop pin for limiting the swinging 35 movement of said hand lever, means for rendering said stop pin inoperative, and friction means for preventing rotation of said crank shaft under the ordinary working pressure on the edge gage.

40 Signed at St. Louis, Missouri, this 4th day of September, 1931.

HARRY W. KRAG.
